SYSTEM FOR ENERGIZING ELECTRICAL
PRECIPITATORS AND THE LIKERalph E. Willison, North Branch, N. J., assignor
to Research Corporation, New York, N. Y., a
corporation of New York

Application September 6, 1951, Serial No. 245,290

8 Claims. (Cl. 183—7)

1.

This invention relates to a system for energizing the electrodes of an electrical precipitator and the like of the type disclosed in the application of Herbert J. Hall, Serial No. 169,019, filed June 19, 1950, for "System for Energizing Electrical Precipitators." More particularly, this invention relates to a system in which the voltage applied to the electrodes of the precipitator is automatically regulated to provide a predetermined rate of sparking between the electrodes.

In the operation of electrical precipitators, contrary to previously accepted ideas, it has been found that optimum performance is attained when the voltage between the electrodes of the precipitator is maintained at a value substantially higher than that at which sparks start to jump between the electrodes. The sparks referred to are not the disruptive power arcs that sometimes occur between the electrodes, but are sparks of relatively low power that occur more or less frequently, depending upon operating conditions, and that do not put sudden serious overloads on the energization system. In an electrical precipitator, there is an optimum rate of sparking above and below which collection efficiency declines. Although the optimum sparking rate will vary for different precipitators, it typically is of the order of fifty to one hundred sparks per minute per precipitator section.

An object of the invention is to provide a system for energizing the electrodes of electrical precipitators that automatically sets and holds the voltage at a value corresponding to substantially optimum sparking rate.

Another object is to provide a relatively simple control system for automatically regulating voltage.

Another object is to provide in such a control system a device that counts each inter-electrode spark to form the basis for control.

These and other objects and advantages of the invention are typically achieved in a system for energizing the electrodes of an electrical precipitator and the like including a voltage regulator, a device responsive to disturbances in the system caused by an inter-electrode spark, means for generating current pulses in accordance with the responses of the spark responsive device, motor means actuated by the current pulses, a rate motor operable at a preselected speed, means including a pair of cooperating relatively movable members providing a control signal in accordance with differential movement of the members, one of the members being driven by the motor means and the other of the members being driven by the

2.

rate motor, and means applying the control signal to the voltage regulator to vary the voltage thereof. The means providing the control signal may take a variety of forms and may include a mechanical differential gearing, a synchro-generator, a potentiometer or the like.

The invention will be described with greater particularity and other of its objects and advantages will be pointed out in the following detailed 10 description of the several exemplary embodiments shown in the drawings.

In the drawings:

Fig. 1 is a diagrammatic view of one form of 15 automatic voltage control system in accordance with the invention;

Fig. 2 is a diagrammatic view of a portion of the system shown in Fig. 1 and including limit switch devices;

Fig. 3 is a diagrammatic view of a portion of 20 another form of automatic voltage control system; and

Fig. 4 is a diagrammatic view of a portion of another such system.

Referring to the drawings, particularly to Fig. 25 1, the automatic voltage control system shown includes an electrical precipitator 10, having a collecting electrode 11 and a complementary discharge electrode 12. The precipitator is energized from a source of current represented by the

30 AC generator 13 feeding the line L₁—L₂. A switch 14 connects the line L₁—L₂ to the winding 15 of a variable autotransformer 16 having a variable output tap 17 and a fixed output terminal 18. The output of the autotransformer is applied to the primary winding 19 of a step-up power transformer 20 through a surge controlling resistor 21. High tension AC from the secondary winding 22 of the power transformer is rectified in a conventional rectifier 23 and the unidirectional pulsating current output of the latter is applied to the precipitator electrodes through a high tension cable 24 and ground connections 25 and 26.

40 Sparks that jump between the electrodes 11 and 12 are sensed in any convenient way, as by 45 a sensing device 27 capacitively related to the high tension cable 24. Each spark causes a disturbance in the cable 24 that registers as a voltage change in the sensing device 27.

A glow tube 28, which may be a strobotron or 50 thyatron, is connected to the capacitive sensing device 27 through a shielded cable 29 and a coupling network including the condenser 30 and resistor 31. The glow tube has a cathode 32, a first grid 33, a second or control grid 34 and an anode 55 35, the control grid 34 being connected to the

spark sensing device. Resistors 36, 37 and 38 provide the required bias for the glow tube grids. A firing condenser 39 is connected across the anode and cathode elements of the glow tube.

A pulsing condenser 40 is connected across the firing condenser 39 through the winding 41 of a solenoid device 42 and a battery 43 or other source of direct current is connected across the pulsing condenser 40 through a switch 44.

The solenoid device 42 includes a movable core or armature 45 having a push rod 46 engaging the periphery of a ratchet wheel 47. A spring 48 is engaged between the collars 49 on the push rod and is anchored to a base 50. Energization of the winding 41 of the solenoid device draws the armature 45 and push rod 46 to the right against the force of spring 48 a distance sufficient to allow the push rod to engage a tooth of the ratchet wheel 47 that is next adjacent to the tooth engaged when the solenoid is deenergized and at rest. Upon deenergization of the solenoid, the spring returns the push rod 46 to the left thus advancing the ratchet wheel one tooth in the counterclockwise direction. The ratchet wheel is advanced in this manner each time the solenoid 42 is energized and deenergized.

The ratchet wheel 47 is connected through a shaft 51 to one input shaft 52 of a mechanical differential gearing 53. The other input 54 of the differential gearing is driven at a preselected speed by a rate motor 55 energized from a source of current 56 through a switch 57 and wires 58 and 59. The speed of the rate motor is controlled by a potentiometer 60. Output shaft 61 of the differential gearing drives a cam 62 of a switch 63 controlling a reversible motor 64 that varies the output voltage of the autotransformer 16.

Reversible motor 64 has a common terminal 65 that is connected to one end of each of the windings 66 and 67 of the motor and through the conductor 68 to one side of the current source 56. When winding 66 is energized, the rotor 69 turns in a direction to move the tap 71 to raise the output voltage of the autotransformer 16, such connection being accomplished by a shaft or linkage designated 70. Energization of the winding 67 turns the rotor 69 in the opposite direction to effect a decrease in the output voltage of the autotransformer.

Terminal 71 of the reversible motor, which is connected to the winding 66 and may be termed the "raise voltage" terminal, is connected to one contact point 72 of the switch 63 and terminal 73, the "lower voltage" terminal of the motor, is connected to contact point 74 of the switch 63. An arm 75, pivoted at 76 has a follower 77 riding on the cam 62 and carries a contact point 78 that closes with contact point 72 when the cam is turned to bring the rise 79 under the follower. When the points 72, 78 are thus closed, the "raise voltage" winding 66 of the reversible motor is energized through the switch 63 and the conductor 80.

Another switch arm 81 having a contact point 82 cooperating with the point 74 energizes the "lower voltage" winding 67 of the reversible motor when the switch cam 62 is rotated to close the switch points 74, 82.

An auxiliary, manually operable switch 83 is employed for manual setting of the output voltage of autotransformer 16 through reversible motor 64.

In operation, switch 14 is closed to energize the electrodes of precipitator 10. Switch 57 is

closed and the setting of autotransformer 16 is adjusted by operation of switch 83 to provide an output voltage producing substantially optimum sparking rate in the precipitator.

Each spark is sensed by the pick-up device 27 and each spark fires the glow tube 28 discharging the firing condenser 39 through the glow tube. After each discharging of the firing condenser, the latter is recharged from the pulsing condenser 40 and battery 43, the switch 44 being closed. The recharging pulse passes through the solenoid winding 41 energizing the solenoid to move the armature 45 to the right. Upon subsidence of the pulse, the spring 48 returns the armature 45 to the left and advances the ratchet wheel 47 one tooth. It is thus seen that each inter-electrode spark results in an advancing movement of the ratchet wheel 47 and that the rate of rotation of the wheel is proportional to sparking rate.

Under conditions of optimum sparking, the speed of rate motor 55 is adjusted by potentiometer 60 to counteract the effect on the differential gearing 53 of the rotation of shaft 52 effected by rotation of the ratchet wheel 47, and the output shaft 61 of the differential gearing remains stationary. The cam 62 of switch 63 remains in its neutral position as seen in Fig. 1 and no adjustment of the autotransformer is made.

If the sparking rate falls below optimum, ratchet wheel 47 turns at a correspondingly slower rate and the output shaft 61 of the differential gearing rotates the switch cam 62 to close switch points 72, 78 and energize the reversible motor 64 in a direction to raise the output voltage of the autotransformer 16. The voltage impressed on the electrodes 11 and 12 of the precipitator is thus raised to increase the sparking rate to slightly above optimum. The speed of ratchet wheel 47 is correspondingly increased and the differential output shaft 61 rotates in a direction to open the switch points 72, 78 to stop the reversible motor.

If the sparking rate should rise substantially above optimum, a reverse action takes place. The speed of ratchet wheel 47 increases, switch points 74, 82 are closed, and reversible motor 64 operates to lower the voltage impressed on the precipitator electrodes to a point at which sparking rate is slightly below optimum. Thus, the voltage impressed on the precipitator electrodes is automatically kept at a value at which sparking rate is substantially optimum.

Should either the rate motor 55 or the ratchet wheel 47 fail to operate, the output shaft 61 of the differential gearing would turn continuously in one direction and the switch cam 62 would rotate continuously, alternately closing the "raise voltage" and "lower voltage" switches and completely vitiating the control action of the system. A mechanism for limiting the rotation of switch cam 62 is shown in Fig. 2.

Referring to Fig. 2, the differential gearing output shaft 61 operates the cam 62 of the rotary switch 63, as in the system shown in Fig. 1. Shaft 61 carries a second cam 84 that has a depressed portion 85 that opens a switch 86 when shaft 61 rotates 90° in the clockwise direction from the position shown in Fig. 2. When the switch 86 is open, the rate motor 55 is deenergized. Shaft 61 carries a third cam 87 having a depressed portion 88 that opens a switch 89 when the shaft rotates 90° in the counterclockwise direction from the position shown in Fig. 2. When switch 89 is open, the spark counting device is inoperative.

In operation, if the rate motor 55 should fail, the control device would appear to call for a lowering of the precipitator energizing voltage. Shaft 61 would turn in a counterclockwise direction until switch 89 is opened by cam 87 and the spark counting system would be deenergized. Conversely, if the spark counting system should fail, the control device would appear to call for an increase in precipitator energizing voltage. Shaft 61 would turn in a clockwise direction until cam 84 opens switch 86 thus deenergizing and stopping the rate motor. The apparatus of Fig. 2 is seen to prevent continuous rotation in one direction of the cam 62 of switch 63.

In Fig. 3 is shown a portion of another form of voltage control system using a differential arrangement for comparing sparking rate with a preselected standard and employing electrical phase shifting principles to effect control.

A synchro generator having a first rotor element 90 and a second rotor element 91 is mounted in bearings so that the first rotor 90 is rotatable in the bearings and the second rotor is rotatable with respect to the first rotor. The generator has a single-phase first rotor and a two-phase second rotor. Connections to S_1 , S_2 , r_1 , r_2 , r_3 , and r_4 are made through slip rings. The first rotor is rotated at a constant speed by a rate motor 55' and driving shaft 92, the speed of rotation being proportional to the desired sparking rate. The second rotor 91 is mechanically driven by the output shaft 51' of a spark converter 93 that includes a motor driven at a speed proportional to actual sparking rate such as the motor having the ratchet wheel 47 of Fig. 1.

Power for excitation of the phase shift comparator 90, 91 and controller to be described is supplied by a transformer 94 having a primary winding 95 supplied with alternating current from a line 96, 97. One secondary winding 98 supplies a phase reference sine wave voltage to the winding of the first rotor 90 of the synchro generator. The second rotor 91, whose windings are physically displaced 90° , has a resistor 99 and a condenser 100 connected in series between the points r_1 and r_3 . The electrical output of the second rotor is taken from the points r_2 and r_4 . The rotor output is a sine wave voltage of constant amplitude, the phase of which is shifted ahead of or behind the phase reference input to the first rotor 90 depending on the speed of the rotor relative to the speed of the stator. The average amount of phase shift in the synchro output is proportional to the deviation in the actual sparking rate, as reflected in second rotor speed, from the desired sparking rate, as reflected in first rotor speed.

A thyratron 101, having the usual cathode 102, grid 103 and anode 104, is energized in the anode-cathode circuit from a secondary winding 105 of the transformer 94. Included in the anode-cathode circuit is a series connected solenoid coil 106 having a cooperating armature 107. Movement of the armature operates a switch designated by the general reference numeral 108. The switch bar 109 is pivoted at 110 and is provided with contact member 111 and 112 cooperating respectively with complementary fixed contact members 113 and 114. A tension spring 115 urges the contact member 112 downwardly and energization of the solenoid coil urges the contact member 111 downwardly through the action of armature 107 on the switch bar 109.

The switch 108 controls the action of a reversible motor such as the motor 64 of the sys-

tem of Fig. 1 to raise and lower the precipitator energizing voltage. The line 116, 117 is connected to a source of current (not shown). Conductor 117 is connected to the common terminal of the reversible motor. Conductor 116 is connected to the switch bar 109. Contact member 113 of the switch is connected through a wire 118 to the "raise voltage" terminal of the reversible motor and contact member 114 is connected to the "lower voltage" terminal through a wire 119. It is thus seen that when the switch contacts 111, 113 are closed, the reversible motor is energized to raise the precipitator voltage and when the contacts 112, 114 are closed, the reversible motor is energized to lower the precipitator voltage.

Bias for the grid 103 of the thyratron 101 is provided by a battery 120 and potentiometer 121 in the cathode-grid circuit.

It will be seen that in the circuit of Fig. 3 the amount of direct current that passes through the thyratron 101 and solenoid winding 106 depends on (a) the D. C. bias on the thyratron grid as applied by the battery 120 and (b) the phase of the phase shifted signal applied to the grid circuit relative to the phase reference voltage in the plate circuit. The smoothing of control action depends on the relative amplitudes of the A. C. and D. C. voltages applied to the thyratron grid.

When the second rotor 91 of the synchro generator is turning faster than the first rotor 90, thus indicating a higher sparking rate than is desired, the current in the plate circuit of the thyratron increases, the armature 107 is drawn downwardly, and switch contacts 112, 114 are closed to effect a lowering of the precipitator voltage. Conversely, when the second rotor 91 is turning slower than the first rotor 90, current in the plate circuit of the thyratron decreases and the spring 115 closes switch contacts 111, 113 to effect an increase in the precipitator voltage.

Another form of control device is shown in Fig. 4. This device is similar to that shown in Fig. 3 except that a differential potentiometer is substituted for the synchro generator of the device of Fig. 3 and changes necessary to the substitution are incorporated in the apparatus of Fig. 4.

A potentiometer, designated by the general reference numeral 122, of the well known circular type, having a resistance element 123 and a slider 124, and terminals 125, 126 and 127, is mounted in bearings so that the case and the enclosed resistance element and slider are rotatable about the axis of the slider while the slider is independently rotatable on its own axis. The case and resistance element are driven by a rate motor 55' through the shaft 92' and the slider is driven in the same direction by the spark converter 93' through the shaft 51''. The terminal 126 of the resistance element is grounded through a slip-ring connection and the other terminal 125 of the resistance element is connected to one pole of a battery 128 through a slip-ring connection. The other pole of the battery is grounded. Slider 124 is connected to the upper end of solenoid coil 106' through a slip-ring connection, and the lower end of the solenoid coil is grounded. It will be seen that the amount of current flowing through the solenoid coil depends upon the position of the slider 124 on the resistance element 123 of the potentiometer which, in turn, depends on the relative speeds of shaft 92' (proportional to the desired rate of sparking) and shaft 51'' (propor-

tional to the actual rate of sparking). As the current in solenoid coil 106' increases, the "lower voltage" contact members 112', 114' are closed because of the pull of armature 107' on the bar of switch 108'. As the current in the solenoid coil decreases, the "raise voltage" contact members 111', 113' close due to the pull of spring 115'.

These control conditions are brought about by differences in rotational speeds of the cooperating resistance and slider elements of the potentiometer 122. When the slider rotates faster than the resistance element, indicating a sparking rate above optimum, the slider advances towards terminal 125 of the resistance element and increased current flows through the solenoid coil 106'. The contact members 112', 114' are closed and the precipitator energizing voltage is lowered. Conversely, a sparking rate lower than optimum causes the slider 124 to move towards the resistance element terminal 126, current in the solenoid coil 106 decreases, switch contact members 111', 113' close, and the precipitator energizing voltage is raised.

From the foregoing description, many modifications of the invention will occur to those skilled in the art without departing from the invention as defined in the claims.

It will also be seen that the present invention provides a system that automatically controls the energizing voltage of an electrical precipitator or the like in accordance with the departure of the sparking rate from a preselected rate.

I claim:

1. A system for energizing the electrodes of an electrical precipitator and the like comprising a voltage regulator, a device responsive to disturbances in the system caused by an inter-electrode spark, means for generating current pulses in accordance with the responses of said spark responsive device, motor means actuated by said current pulses, a rate motor operable at a preselected speed, a motor for varying the voltage of said voltage regulator; and differential drive means for energizing said motor driven by said motor means and said rate motor.

2. A system as defined in claim 1 wherein said differential drive means includes a mechanical differential gearing.

3. A system as defined in claim 1 wherein said differential drive means includes a synchro-generator.

4. A system as defined in claim 1 wherein said differential drive means includes a potentiometer the resistance element and slider of which provide the relatively movable members thereof.

5. A system as defined in claim 1 wherein said differential drive means includes a mechanical differential gearing driving a rotary electrical switch and including means limiting the rotary movement of said switch.

6. A system for energizing the electrodes of an

electrical precipitator and the like comprising a voltage regulator, a reversible electric motor connected to vary the voltage of said regulator, switch means controlling said reversible electric motor, a device responsive to disturbances in the system caused by an inter-electrode spark, means for generating current pulses in accordance with the responses of said spark responsive device, a rotary electric motor actuated by said current pulses, a rate motor operable at preselected speed, and a mechanical differential gearing having two input shafts and an output shaft, said rotary electric motor being connected to drive one of the differential input shafts, said rate motor being connected to drive the other of said input shafts, and the output shaft of said differential gearing being connected to operate the switch means controlling said reversible electric motor.

7. A system for energizing the electrodes of an electrical precipitator comprising means for varying the voltage applied to said electrodes, a device responsive to disturbances in the system caused by an inter-electrode spark to continuously integrate the occurrences of said disturbances with respect to time to produce a control force which is a function of the continuous rate of production of said sparks, a control device operatively connected to said voltage varying means and to said disturbance-responsive means to vary the control action thereof in accordance with the value of said control force and therefore in accordance with the current integrated rate of said pulses.

8. A method of energizing the electrodes of an electrical precipitator to produce an optimum sparking rate comprising sensing disturbances in the system caused by an interelectrode spark, continuously integrating the occurrences of the sensed disturbances with respect to time to produce a control force which is a function of the continuous integrated rate of production of said sparks, varying the voltage applied to said electrodes in accordance with the value of said control force so as to maintain the pulse rate at an optimum value.
